(57) **CLAIM**

The ornamental design for a tamper-evident container, as shown and described.

DESCRIPTION

FIG. 1 is a front, right, top perspective view of a tamper-evident container, showing my new design;

FIG. 2 is a rear, left, bottom perspective view thereof;

FIG. 3 is a front elevational view of the enlarged scale

thereof;

FIG. 4 is a rear elevational view of the enlarged scale

thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof;

FIG. 9 is an enlarged view of detail 9 in FIG. 1;

FIG. 10 is an enlarged view of detail 10 in FIG. 1;

FIG. 11 is an enlarged view of detail 11 in FIG. 1;

FIG. 12 is an enlarged view of detail 12 in FIG. 2;

FIG. 13 is a front, right, top sectional perspective view of

13-13 along the line in FIG. 3;

FIG. 14 is an enlarged view of detail 14 in FIG. 7;

FIG. 15 is an enlarged view of detail 15 in FIG. 13;

FIG. 16 is an enlarged view of detail 16 in FIG. 13; and,

FIG. 17 is an enlarged view of detail 17 in FIG. 13.

The dash-dot-dash broken lines are for notating enlarged

views and form no part of the claimed design.

1 Claim, 17 Drawing Sheets
